Inventor

Maurice Alland,

By *J. Stuart Freeman.*
Attorney

UNITED STATES PATENT OFFICE

MAURICE ALLAND, OF ATLANTIC CITY, NEW JERSEY

THIMBLE

Application filed January 20, 1930. Serial No. 421,960.

The object of the invention is to provide improvements in sewing thimbles, both for domestic use and for the professional trade, in each case the thimble being intended to 5 utilize the additional function of picking up needles, pins, and similar magnetizable articles.

Another and more specific object is to provide a domestic or professional's thimble 10 with an annular ring about its normal free end portion, said ring being so related to the thimble that it does not interfere with the function of the latter, yet forms a flange which operates to prevent a needle in contact 15 with a side of the thimble from slipping from or across the end of the latter, and at the same time comprises an outer surface adapted for use in smoothing darned or mended surfaces of fabric.

20 A further object is to provide the combination of a thimble with an annular ring, having transverse cuts in the diametrically opposite portions of its outer plane surface, to define the limits of its magnetized poles.

25 With these and other objects in mind, the present invention comprises further details of construction and operation, which are fully brought out in the following description, when read in conjunction with the accompanying drawings, in which Fig. 1 is a 30 side elevation of a professional's thimble embodying the invention; Fig. 2 is a vertical diametrical section of the same; Fig. 3 is a top plan view of the same; and Fig. 4 is a 35 perspective view of a domestic thimble also embodying the invention.

Referring to Figs. 1 to 3 inclusive, the usual slightly conical thimble member 5 is provided upon its outer surface with closely 40 adjacent recesses or cavities 6 for engagement with the butt end of a needle (not shown) in the usual course of sewing or stitching, said member at one end being provided with an outwardly and reversely curved stiffened 45 flange 7, while its opposite end 8 is open and is surrounded exteriorly by a plain cylindrical surface 9, upon which is secured by any suitable means the corresponding inner surface 10 of a cylindrical member 11, preferably formed of steel or other magnetizable

metal. This member 11 is provided at its free end portion with a radially inwardly directed flange 12, which serves to arrest the movement of the ring with respect to the thimble proper, when the former is being 55 driven upon the end of the latter, the flange also serving to protect the free edge portion of the thimble.

It will be noted that the outer plane surface 13 of the ring 11 is cut by diametrically extending saw-cuts, grooves, or other suitable means 14 for separating the opposed portions of said ring and thereby defining the limits of its magnetic poles, it being possible, and in cases desirable, to fill in the saw-cuts 14 or the like with a suitable non-magnetizable metal, such as copper, brass, or the like, in order to eliminate the interruption of the continuity of the ring surface 13.

Referring to Fig. 4, a domestic thimble of 70 any well-known shape is illustrated as comprising conical side walls 15, terminating at the base in a reinforcing flange 16, and closed by an end wall 17, said side and end walls being provided with recesses for receiving 75 the butt ends of needles, as hereinbefore referred to, during the usual course of sewing, stitching, and the like. In this form of the device, there is driven upon the closed end portion of the thimble and secured thereto 80 in any suitable manner, an annular ring 18 of steel or other magnetizable metal, provided with transverse saw-cuts 19, corresponding to the cuts or recesses 14 shown in Figs 1 to 3 inclusive.

With each of these types of thimbles as here described and as illustrated in the drawings, those portions of the rings 11 and 18 upon the opposite sides of the respective saw-cuts 14 and 19 are characterized as comprising magnetic poles of opposite polarity, so that an operator having one of these improved thimbles upon his finger, need simply invert the thimble in contact with a needle, or a similar light magnetizable article, and upon raising the thimble, said article will be found to have adhered to the magnetic ring in any one of an infinite number of directions crossing the lines of the respective saw-cuts. However, as the strength 95 100

of the magnetic ring in each case is only sufficient to lift relatively small articles, as above stated, it offers but slight resistance to the manual removal of such articles from the thimble ring after it has been raised from the table or other surface upon which the article formerly rested.

Having thus described my invention, what I claim and desire to protect by Letters Patent of the United States is:—

1. A sewing thimble, in combination with an annular ring of magnetizable metal secured thereto and provided with transversely extending reduced portions to define the limits of its magnetic poles.

2. A sewing thimble, having a substantially cylindrical end portion, and an annular ring of magnetizable metal secured upon said end portion, said ring being of less axial extent in diametrically opposite portions, to define the limits of its magnetic poles.

3. A sewing thimble, having a substantially cylindrical end portion, and an annular ring of magnetizable metal secured upon said end portion and comprising a radially inwardly extending flange, diametrically opposite portions of said ring being partially severed transversely by means of saw-cuts, to define the limits of its magnetic poles.

30 In testimony whereof I have affixed my signature.

MAURICE ALLAND.
